Primary Examiner — Cynthia R Underwood(57) **CLAIM**

The ornamental design for a multi-segment rail mounting structural connector, as shown and described.

DESCRIPTION

FIG. 1 is a front, top, and left perspective view of a multi-segment rail mounting structural connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof; and,

FIG. 9 is a combined perspective view thereof.

The broken lines shown in the drawings represent portions of the multi-segment rail mounting structural connector that form no part of the claimed design.

1 Claim, 9 Drawing Sheets(56)
